TOY SPACE EXPLORATION VEHICLE

Jack Rosenthal, Fivescissburg Ring,
South London, England

Filed Dec. 29, 1969, Ser. No. 20,677

Term of patent 3½ years

Int. Cl. D21—02

U.S. Cl. D34—15

FIG. 3.

FIG. 1.

FIG. 2.

FIG. 4.

FIG. 1 is a side elevational view showing the design of a toy space exploration vehicle according to this invention;

FIG. 2 is an end elevational view of the vehicle which is substantially identical in appearance when viewed from the other end;

FIG. 3 is a top plan view thereof; and

FIG. 4 is a bottom plan view thereof.

I claim:

The ornamental design for a toy space exploration vehicle, substantially as shown and described.
